UNITED STATES PATENT OFFICE.

JOHN C. DOANE, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 926,054.

Specification of Letters Patent. Patented June 22, 1909.

Application filed March 11, 1908. Serial No. 420,337.

To all whom it may concern:

Be it known that I, JOHN C. DOANE, a citizen of the United States, residing in Hartford, in the county of Hartford and 5 State of Connecticut, have invented certain new and useful Improvements in Type-Writing Machines, of which the following is a specification.

This invention relates to the ribbon-operating mechanisms of typewriting machines, especially to those described in my co-pending application No. 378,357, filed June 11, 1907, (Patent No. 891,047) in which are shown two independently vibratable ribbons 10 and winding mechanism therefor mounted upon the well-known Underwood front strike writing machine. In said application, the ribbons are shown carried upon two pairs of spools lying in front of the platen, with shiftable means for winding the spools of either pair, and means for vibrating the ribbon which is carried by the winding spools. The present invention is in the nature of an improvement upon said mechanism, and also upon the mechanism disclosed 25 in the pending application No. 283,440, (Patent No. 883,470) of John C. McLaughlin. In said McLaughlin application, each ribbon spool is provided with a gear, and 30 two winding gears are shiftable into and out of mesh with the spool gears to wind either ribbon, while the other remains idle.

The principal object of the present invention is to improve, and simplify the ribbon winding means, especially with a view to adapting the two-ribbon devices to be applied to existing types of machines.

In said applications ribbon shift keys are provided upon the front of the machine, to 40 operate a rock shaft which extends rearwardly to connect to the ribbon winding and vibrating devices.

In carrying out my present invention, I mount upon the rock shaft a lever, one arm 45 of which extends up and the other down, and I connect the ends of the lever to swivelled hangers which carry the winding gears, so that the gears may be moved either toward each other or away from each other, to connect with either one or the other pair of spools. The connection between said lever and said hangers is effected by means of 50 simple links, and the entire mechanism is compact and readily applied to existing 55 types of machines.

Other features and advantages will hereafter appear.

In the accompanying drawings, Figure 1 is a front elevation partly in section showing the inside pair of spools connected to 60 the winding mechanism, and also showing a type in printing position. Fig. 2 is a plan, and Fig. 3 a side elevation of the ribbon mechanism. Fig. 4 is a sectional rear elevation of a detent for holding the ribbon- 65 shifting mechanism in either of three positions.

Upon the front side of a platen 1 strike types 2, carried upon type bars 3 and adapted to strike through either a front ribbon 4 or a rear ribbon 5, which are of different colors or qualities. The front ribbon 4 is wound upon a pair of spools 6, 7 mounted at opposite sides of the printing point and in front of the platen, with their edges to the 75 latter and contained in a pair of cups 8, 9. The ribbon which extends between these spools is threaded through a vibrator 10 standing in front of the platen. The rear ribbon 5 is wound upon a pair of spools 11, 12, carried in cups 13, 14 and threaded through a vibrator 15, which is mounted between the vibrator 10 and the platen. It will be seen that the pair of spools 6, 7 is 80 between the spools 11, 12, so that two spools 85 lie edge to edge upon each side of the printing point; the rear ribbon 5 extending in rear of the cups 8, 9.

In said Underwood machines, a universal bar or frame 17 mounted at its rear end 90 upon upright rocker-arms 18 is reciprocated backwardly and forwardly at the type strokes. The rocker arms 18 operate a slotted arm 20. The latter engages a pin 21, of a crank 22 fixed upon a rock-shaft 23, the latter having at each side of the machine an arm 24 carrying a pawl 25 to engage a ratchet wheel 26 for winding the ribbon. In said Underwood machine a shifter bar 27 (shown diagrammatically) throws one 100 pawl 25 into action and the other pawl 25 out of action, thus reversing the longitudinal travel of the ribbon. By means of said pawl and ratchet mechanism, there is rotated at each side of the machine a pair of miter gears 28, 29, the gears 29 fixed upon the lower ends of vertical shafts 30, 31, which at their upper ends carry gears 32, 33. The gear 32 is mounted between gears 34, 35 105 carried by shafts 36, 37 upon which are 110

mounted the spools 11, 6. The gear 33 is mounted between adjacent gears 38, 39 fixed upon shafts upon which are mounted spools 7, 12.

- 5 The winding gear shafts 30, 31, are mounted in hangers 40, 41, which at their lower ends are swiveled upon studs 42 projecting rearwardly from bars 43 secured upon the ribbon spool brackets 44; the latter secured 10 by screws 45 upon the framework 46 of the machine. At their upper ends the hangers are confined by headed screws 47 secured in the brackets 44 and working in slots 45^a formed in the hangers. At its upper end 15 each hanger is bent rearwardly to form an ear 48 perforated to form a bearing for the shaft; and near its lower end an ear 49 is secured to each hanger and perforated to form a bearing for the lower end of the shaft. The pivots 42 are placed so as to 20 permit the required swinging movement of the gears 29 without becoming unmeshed from the gears 28.

The shifting of the winding gears is 25 effected by means of keys 50, 51 mounted at the front of the machine, upon a rock shaft 52, which extends rearwardly and carries a lever 52, which extends both upwardly and downwardly from said shaft. The upper 30 end may be connected by a short link 54 to the swiveled hanger 41, and the lower end of said lever is connected by a long link 55, which extends across the machine beneath the type bars 3, to the other swiveled hanger 40. 35 When key 51 is depressed, the winding gears are shifted from the Fig. 1 to the Fig. 2 position; the link 54 pulling the hanger 41, shaft 31, and gear 33 to the right, Fig. 1, and the link 55 thrusting the gear 32 to the 40 left, so that the spools 11, 12 are caused to wind, and the spools 6, 7 to remain stationary. When the key 50 is depressed, the parts are shifted back from the Fig. 2 to the 45 Fig. 1 position, and the ribbon 4 is caused to wind at the type strokes. The detent 56 serves to hold the parts in either position.

The link 55 is made up of two parts, one of which 57 is connected to the other by 50 screws 58 engaging slots 59, to permit lengthening or shortening of the link, and effect fine variations in the relative positions of the winding gears 32 and 33, so that both may be caused to mesh properly with the spool gears at the operation of the ribbon keys.

55 The ribbon vibrators 10, 15, are carried upon levers 60 and 61 respectively, whereby that ribbon is vibrated which is carried upon the winding spools. Said levers are fulcrumed together upon a stud 62 carried upon 60 a bracket 63 secured upon a platen shift rail 64. Said levers have wrists 65, 66 respectively, either of which may be engaged by a yoke 67, connected by a link 68 to a crank 69 extending up from the rock shaft 52. 65 Said yoke 67 has vertical slots 70 formed in

its opposite cheeks 71, 72, adapted to be engaged by the wrists 65, 66. The yoke is adjustably mounted upon a standard 73 rising from the universal bar frame 17, and moves backwardly and forwardly at the type 70 strokes, and by means of its engagement with either one or the other of the wrists 65, 66 causes the corresponding ribbon to vibrate to cover the printing point. When the key 51 is depressed to cause outer spools 75 11, 12 to wind, the crank 69 is swung to the right as at Fig. 2, to engage the vibrating yoke 67 with the wrist 66 upon the lever 61, which operates the vibrator 15 carrying said ribbon. When the key 50 is depressed to 80 cause the inner spools to wind, the yoke 67 is thrust to the left at Fig. 2, to become disengaged from the wrist 66 and engaged to the wrist 65 to cause the vibrator 10 to vibrate the front ribbon 4, which is carried 85 upon said spools.

It will be understood by reference to Fig. 4, which shows a rear view of the detent, that when the key 51 is depressed the detent 56 is swung over from the Fig. 4 position, 90 until its pin or tooth 74 engages a hole 75, thereby connecting the other ribbon spools to the winding mechanism, and the other vibrator to the universal bar 17. When it is desired that neither vibrator shall operate, 95 the arm 56 is swung until the pin 74 engages a midway hole 76 in the plate 77; and at this time the winding gears stand in midway positions, so that neither spool is wound at the type strokes. 100

Having thus described my invention, I claim:

1. In a typewriting machine, the combination with two pairs of spools, each spool provided with a gear, of two winding gears 105 mounted upon shafts vibratable to connect the winding gears with one or the other pair of spool gears, a shift lever operated by a finger-piece and connected to one of said shafts to vibrate it, and a link extending 110 from said lever to vibrate the other shaft in the opposite direction.

2. In a typewriting machine, the combination with two pairs of ribbon spools, each spool provided with a gear, of two winding gears mounted upon shafts vibratable to connect the winding gears with one or the other pair of spool gears, a key-bearing rock shaft, a lever upon said shaft and extending in opposite directions therefrom and connected 115 at one end to one of said winding shafts, and a link extending from the other end of said lever across the machine to vibrate the other of said shafts. 120

3. In a typewriting machine, the combination with two pairs of ribbon spools, each spool provided with a gear, of two winding gears mounted upon shafts vibratable to connect the winding gears with one or the other pair of spool gears, a key-bearing rock 125 130

- shaft, a lever upon said shaft and extending in opposite directions therefrom and connected at one end to one of said winding shafts, a link extending from the other end 5 of said lever across the machine to vibrate the other of said shafts, and means for effecting adjustment of the end of said link.
4. In a typewriting machine, the combination of two pairs of spools, each spool 10 provided with a gear, two winding gears for said spools, and means for vibrating said winding gears to engage with either pair of spool gears and for effecting fine adjustment of said winding gears relatively to 15 each other.
5. In a typewriting machine, the combination with a platen, of two pairs of spools, gears for all of said spools, two winding gears, a finger-piece, means controlled by 20 said finger piece for shifting said winding gears into mesh with either pair of spool gears, and means for effecting fine adjustment in the relative positions of the winding gears.
25. 6. In a typewriting machine, the combination with two pairs of ribbon spool gears, of two pairs of winding gears connected by a link and shifted by a finger-piece, and means for enabling variations to be effected 30 in the length of said link.
35. 7. In a typewriting machine, the combination with two pairs of spools, each spool provided with a gear, of two winding gears mounted upon shafts vibratable to connect the winding gears with one or the other pair of spool gears, a shift lever extending in opposite directions from its fulcrum and connected at one end by a short link to one 40 of said shafts to vibrate it, and connected at its other end by a long link to the other of said shafts.
45. 8. In a typewriting machine, the combination with two pairs of ribbon spool gears, of two winding gears, hangers upon which said winding gears are mounted, and a key operated lever connected to said hangers to shift the winding gears from one to the other pair of spool gears.
50. 9. In a typewriting machine, the combination with two pairs of ribbon spool gears, of two winding gears, shafts upon which the winding gears are mounted, pinions on said shafts, drive pinions meshing with said pinions swiveled hangers carrying said shafts, and key-operated means connecting said hangers to shift the winding gears from one to the other pair of spool gears.
55. 10. In a typewriting machine, the combination with two pairs of ribbon spool gears, of two winding gears, shafts upon which the winding gears are mounted, swiveled 60 hangers carrying said shafts, a key-operated lever extending in opposite directions from its fulcrum, and means connecting the ends of the lever to said hangers respectively to move the winding gears either toward or away from each other into engagement with either one or the other set of spool gears.
65. 11. In a typewriting machine, the combination with two pairs of ribbon spool gears, of two winding gears, shafts upon which the winding gears are mounted, swiveled hangers carrying said shafts, a key-operated lever extending in opposite directions from its fulcrum, means connecting one end of the lever to one of said hangers, and a link extending from the lever to the other of said hangers.
70. 12. In a typewriting machine, the combination with two pairs of ribbon spool gears, of two winding gears, shafts upon which the winding gears are mounted, swiveled hangers carrying said shafts, a key-bearing rock-shaft, a lever extending in opposite directions from said rock shaft, a short link connecting one end of the lever to one of said hangers, and a long link connecting the other end of said lever to the other of said hangers.
75. 13. In a typewriting machine, the combination with two pairs of ribbon spools and spool winding devices, of a finger-piece having means to effect connection between the spool-winding devices and either pair of ribbon spools, vibrators for the ribbons, levers connected to the vibrators and provided with operating wrists, an actuator vibrating at the key strokes and having means to engage either of said wrists, and means connected to said finger-piece for 80 shifting said actuator into engagement with either wrist and out of engagement with the other.
85. 14. In a typewriting machine, the combination with two pairs of ribbon spool gears, of two winding gears, shafts upon which the winding gears are mounted, swiveled hangers carrying said shafts, a key-bearing rock-shaft, a lever extending in opposite directions from said rock shaft, means connecting one end of the lever to one of said hangers, and a link connecting the other end of said lever to the other of said hangers, a pair of levers for vibrating the ribbons, each lever having a wrist, an actuator vibrating at the key strokes, and means connecting said actuator to said rock shaft to shift it 90 into engagement with either of said wrists.
95. 105. 110. 115. JOHN C. DOANE.
